UNITED STATES PATENT OFFICE.

EDWARD W. MEREDITH, OF BLOOMSBURG, PENNSYLVANIA.

FLUID-PRESSURE MOTOR.

1,211,209.

Specification of Letters Patent.

Patented Jan. 2, 1917.

Application filed December 23, 1915. Serial No. 68,381.

To all whom it may concern:

Be it known that I, EDWARD W. MEREDITH, a citizen of the United States of America, residing at Bloomsburg, in the county of Columbia and State of Pennsylvania, have invented certain new and useful Improvements in Fluid-Pressure Motors, of which the following is a specification.

My present invention relates to improvements in fluid pressure motors and applies directly to the construction of the motor described and claimed in my patent dated November 2, 1915, No. 1158525. In using the structure which forms the subject matter of said patent I find that its operation and efficiency are enhanced by the use of means providing communication at all times, and especially when the parts of the machine are in position so that the fluid pressure is equalized, to maintain an even pressure of the steam even when the cubical contents of the cylinder at the stem side of the piston is decreasing, as will be hereinafter more fully pointed out.

In the drawings Figure 1 is a horizontal sectional view of the motor and its connections. Fig. 2 is a plan view, enlarged of the controlling valve. Fig. 3 is a sectional view of the controlling valve and its casing. Fig. 4 is a side elevation of the motor adapted for use as a hydraulic motor with an air chamber forming part of the motor.

I have illustrated the device as either a steam or compressed air motor and also as a hydraulic motor, and while I shall herein-after refer to these two modifications as steam and hydraulic motors, it will be understood that the invention is capable of use as a single acting engine in many other forms not herein referred to.

For convenience of illustration it may be stated that the piston stem 1 and its piston 2 are in direct connection with the table of a brick machine, at the threaded end 3 of the stem, and it will of course be recognized that the table is a reciprocable one and is to be drawn to the right on the working stroke of the piston in its cylinder 4. The table is moved to the left to return the piston, by other power mechanism forming part of the brick machine.

The cylinder is provided with the usual heads 5 and 6 and has a relief cock 7 opening therein to regulate a cushion of compressed fluid, in the nature of a dash pot in

the end of the cylinder, at the right, while the head 5 is provided with a usual stuffing box as 8. At 9 and 10 the usual end ports of the cylinder are indicated, the former for admission of fluid and the latter for the exit of fluid or steam.

The motive fluid, or steam for actuating the piston is controlled by the piston valve 11 which is reciprocable in its casing 12 by power such as a cam or crank not shown applied at the end of the stem 13. The casing at one end is in communication with the cylinder 4 through port 9 by the pipe 14 which is the inlet pipe for live steam to the cylinder for operating the piston. A small branch pipe 14^a having a check valve 14^b projects from the pipe 14 and communicates with the interior of the cylinder 4 at the left end. The check valve opens toward the cylinder and aids in regulating the pressure therein and this connection by admitting fluid pressure to the cylinder at the left of the piston forms a dash-pot at the left end of the cylinder, to cushion the piston at the end of its stroke to the left.

A pipe 15 which also extends from the left end of the casing 12, passes around to the right end of the cylinder and communicates with its interior through the head 6. This pipe has a check valve 16 therein and the communication is provided between the cylinder and casing to prevent the formation of a vacuum at the right end of the cylinder when the piston moves to the left.

The valve casing is provided with annular recesses or ports 17 and 18, the former for the inlet to the cylinder and the latter for the exhaust from the casing, and this port 18 permits passage of exhaust steam to the exhaust pipe 19 of the casing. A third port is shown in the valve casing, indicated at 20 and this port is in communication with the interior of the cylinder through the cylinder port 10.

The valve 11 has a passage 21 therethrough, open at the left end and closed at the right end by the threaded end of the valve stem 13, but at the right end of the piston valve its central bore is provided with four radial ports as 22 which establish communication between the interior of the valve casing and the interior of the valve itself. The valve is also cut away and its exterior diameter reduced to form an annular space 23 within the casing by means of which com-

munication between the inlet pipe 24 to the casing and inlet pipe 14 of the cylinder through the port 17 in the casing.

The bore of the casing is grooved at 23' 5 and this groove opens into the port 17 (Figs. 1 and 3). The purpose of this groove is to permit passage of steam or other motive fluid at all times, and especially when the valve 11 is in equalizing position (Fig. 1) 10 in order to maintain an even pressure. This free flow of steam offsets the fall in pressure at the stem side of the piston due to the decreased cubical volume of the cylinder. I have found in actual use that the difference in cubical contents of the cylinder 15 at the stem side of the piston causes a fall in pressure at that side of the piston when the piston is traveling to the left, thus weakening the engine on this stroke.

20 To understand the utility of maintaining an even pressure on both sides of the piston 2, on the equalization stroke, it will be noticed that the piston rod 1 which extends a distance outside the cylinder, makes the piston a differential one, that is the piston 2 has a greater superficial area in the cylinder on its head side than it has on its rod side, the difference in area being determined by the cross sectional area of the piston 25 rod. Now suppose that the cross section area of the rod is 2 square inches, and we equalize the pressure in the cylinder say at 100 lbs. the greater pressure at the right side of the piston will move it to the left, therefore the piston has a pressure of 200 30 lbs. more on the head side than on the rod side. This power is used in overcoming the friction in the carriage of the brick cutting table, but it will be noticed that the 35 supply of live steam is cut off from the cylinder 4 by the valve 11, when the piston 2 is making this stroke and the steam in the rod end of cylinder 4 is flowing to the other end of cylinder 4 and around the piston 2, and the piston rod 1 is moving 40 out of cylinder 4 to the atmosphere thereby increasing the cubical contents of the cylinder 4 in exact proportion to the amount of cubic inches contained in the piston rod 45 1 that is removed from the cylinder 4 to the atmosphere through the cylinder head 5 and stuffing box 8. As before stated, the live steam is shut off from the cylinder and the steam within the cylinder must be reduced in pressure while the piston is making 50 its stroke to the left so that the farther the piston moves to the rod end of the cylinder 4 the lower the pressure of equalized steam must be, thereby weakening the engine on the latter part of this stroke. This 55 reduction of pressure is caused by the increase of the cubical contents of the cylinder as the piston 2 and its rod travel to the left. Now to overcome this condition 60 65 I utilize the groove 23' in the valve casing

12 so that when the valve 11 is moved to the equalizing position the cylinder 4 will be in communication with chamber 23 which contains live steam at all times. As the piston 2 moves to the left the steam will flow 70 around the end of the valve 11, thereby maintaining a constant pressure in the cylinder on the outward stroke of the piston.

In Fig. 4 the motor is illustrated as a hydraulic motor, and I employ a pipe 14' 75 and equip it with a regulating valve 15' and an air chamber 16' between the controlling valve and the stem side of the piston. This air chamber forms an effectual means for performing the functions of the 80 groove above referred to, and equalizes the pressure of water throughout the device.

In Fig. 1 the piston has finished its working stroke and has pulled the table to the right. Admission of live steam to the casing is cut off except to the space 23 but from here the live steam may pass by way of the small groove 23' to port 17 thence through pipe 14 to the left side of the piston and through the centrally bored valve 90 11 and its ports 22 and ports 20 and 10 to the cylinder at the right side of the piston. By this arrangement of parts the pressure throughout the whole device is equalized, so that the return reciprocation 95 of the power driven table (not shown) will move the piston to the left in Fig. 1. After the piston has been moved to the left, the controlling valve is actuated and moved to the left also and live steam is admitted in 100 large quantities through space 23, port 17 and pipe 14 to the cylinder at the left of the piston head, but passage of steam to the right in the casing or through the valve bore is prevented. However, steam is exhausted from the right side of the cylinder 105 through ports 10, 20, 18 22 and pipe 19, a vacuum being prevented by the presence of the check valve 16 as before stated. The admission of fluid pressure to the left of 110 the piston of course moves it to the right and thus the working stroke of the motor is accomplished.

What I claim is:—

1. In a single acting motor, the combination with its cylinder and its piston, of a casing having a valve therein and a motive fluid inlet, ports at the ends of the cylinder in communication with ports in the casing, said valve having means for equalizing the pressure in the cylinder upon the return stroke of the piston and also adapted to admit motive fluid to the cylinder at one end and exhaust the same from the cylinder at the other end, and means 115 for permitting free flow of motive fluid throughout the motor when the parts are 120 in position under equalized pressure.

2. In a single acting motor, the combination with its cylinder and its piston, of 130

a casing having a groove and also a valve therein and a motive fluid inlet, ports at the ends of the cylinder in communication with ports in the casing and one of said 5 casing ports being the terminus of the groove in the casing for permitting free flow of motive fluid throughout the motor when the parts are in position under equal- ized pressure, said valve having means for equalizing pressure in the cylinder, and 10 adapted to admit pressure to the cylinder at one end and exhaust it from the other end of the cylinder.

In testimony whereof I affix my signature.

EDWARD W. MEREDITH.
